(57) **CLAIM**

The ornamental design for an electrical connector, as shown and described.

DESCRIPTION

FIG. 1 is a front, bottom and left-side perspective view of an electrical connector showing my new design;

FIG. 2 is a front perspective view thereof;

FIG. 3 is a rear perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof;

FIG. 9 is a bottom plan view thereof;

FIG. 10 is an enlarged partial view of the area 10 indicated in FIG. 1;

FIG. 11 is an enlarged partial view of the area 11 indicated in FIG. 2;

FIG. 12 is an enlarged partial view of the area 12 indicated in FIG. 3;

FIG. 13 is an enlarged cross-sectional view taken along line 13-13 in FIG. 4;

FIG. 14 is an enlarged cross-sectional view taken along line 14-14 in FIG. 4;

FIG. 15 is an enlarged cross-sectional view taken along line 15-15 in FIG. 4;

FIG. 16 is an enlarged partial view of the area 16 indicated in FIG. 4; and,

FIG. 17 is an enlarged partial view of the area 17 indicated in FIG. 5.

The dash-dash broken lines illustrate portions of the electrical connector that form no part of the claimed design.

Also, the dash-dash broken lines in FIG. 13, FIG. 14 and FIG. 15 depict the surfaces at the cut marks and form no part of the claimed design. The dot-dash broken lines illustrate the boundary of the claimed design and form no part of the claimed design. The dot-dot-dash broken lines illustrate the boundary of the portions shown enlarged and form no part of the claimed design.
